CLAIM

The ornamental design for a camera mount, as shown and described.

DESCRIPTION

FIG. 1 is a top, front, and right side perspective view of a camera mount showing our new design;
FIG. 2 is a top plan view thereof;
FIG. 3 is a left side elevation view thereof;
FIG. 4 is a front elevation view thereof;
FIG. 5 is a right side elevation view thereof;
FIG. 6 is a rear elevation view thereof; and,
FIG. 7 is a bottom view thereof.

The broken lines showing in FIGS. 1-7 depict environmental subject matter and form no part of the claimed design.
